UNITED STATES PATENT OFFICE.

SHAKIR S. JERWAN AND FUAD S. JERWAN, OF NEW YORK, N. Y.

AEROMOTOR-BOAT.

1,049,865.

Specification of Letters Patent.

Patented Jan. 7, 1913.

Application filed March 24, 1911. Serial No. 616,655.

To all whom it may concern:

Be it known that we, SHAKIR S. JERWAN and FUAD S. JERWAN, citizens of the United States, and residents of the city of New York, boroough of Manhattan, in the county and State of New York, have invented a new and Improved Aeromotor-Boat, of which the following is a full, clear, and exact description.

10 Our invention is an aeroplane having a motor boat attachment so that the aeroplane can alight upon a body of water and propel itself over the surface thereof, or be caused to rise from the surface of the water and 15 resume its flight, whenever the operator desires.

To this end it comprises a novel arrangement of parts for the purpose of supporting and balancing the structure of the aeroplane when it rests upon the surface of the water and is propelled thereover, all of 20 which will be fully pointed out in the specification and particularly specified in the claims appended thereto.

25 Reference is to be had to the accompanying drawings forming a part of this specification, in which the same characters of reference indicate the same parts in all the views.

30 Figure 1 is a top view of our improved aero-motor boat, the lifting plane or wing at the right having the covering thereof removed to show the framework of the wing; Fig. 2 is a front view of the invention; Fig. 3 is a side elevation; Fig. 4 is a vertical longitudinal section through the forward part of the aero-motor boat, showing the arrangement of power apparatus and controlling levers on the interior thereof; and Fig. 5 is a side elevation of a modified form of motor boat attachment for an 35 aeroplane.

Our improved aeroplane comprises a central framework 1, from the sides of which, 40 adjacent the front portion thereof, extends the framework of the lifting planes or wings 2. This framework, as shown on Fig. 1, comprises a suitable number of extended transverse rods connected together 45 by means of cross braces and diagonal stay wires, to make a compact structure. On top of this framework is placed the covering 3 of the wings, which may be of canvas or any other suitable cloth, and each of the wings

3 has an opening 4 therein, the area of 55 which is controlled by means of a sliding cover 5, moving upon guides 6. The cover is held by a spring 7 in closed position, and is moved by means of cords 8, operated by levers which are controlled from a point 60 near the seat of the aviator, so that the slides 5 can be pulled against the action of the spring 7 to uncover more or less of the openings 4. This will so regulate the effective area of the planes 3, that the machine 65 can be prevented from tilting when making its flight, or caused to resume a horizontal position when it does tilt, simply by uncovering part or the whole of the opening 4 on that side of the plane which is highest. 70 This will diminish the effective area of the higher wing and cause the same to sink, bringing the machine back to equilibrium. This arrangement of openings is not claimed in this application, but is fully described 75 and claimed in our co-pending application Serial Number 614,518, filed March 15, 1911.

The main frame 1 of the aeroplane has tail planes 3' extending rearwardly from the wings 3, and terminating in horizontal 80 rudders 8', which flank the vertical rudder 9, mounted to swing at the rear end of the main frame 1. Brace wires 10 are connected to the ends of the framework 2 of the main wings, and the rear of the framework 1, to 85 strengthen the framework of the entire apparatus and make a rigid structure. Stay wires 11 are also arranged on top of the machine, these stay wires being joined at their outer ends to suitable points of the wing 90 framework 2, and at their inner ends to a central ridge bar 12, carried above the main framework 1.

Fastened to the forward part of the main frame 1 at each side thereof and extending 95 down below the bottom of this framework are a number of vertical ribs 13, which form the framework of a boat-shaped car 14. This car is made up of a number of plates of light metal, such as aluminum, or any other suitable substance, which are fastened to the ribs 13 to form a partly closed cabin. In the front of the boat-shaped car are windows 15, one on either side of the center; and beneath the floor of the car is an air 100 chamber 16, to increase the buoyancy of our 105 aero-motor boat.

Resting upon suitable supports mounted

upon the floor of the boat-shaped car 14 is the engine 17, having a crank-shaft 18, which is connected by means of suitable shafting to a propeller 19 at the stern of the 5 car, this propeller serving to drive the aero-motor boat through the water when the entire machine is resting upon the surface. A suitable clutch is provided to couple up or uncouple the propeller 19 from the shaft 18, 10 this clutch being controlled by a lever 18', from the operator's seat.

On the front end of the crank shaft 18 is an idle pulley 20 and a fixed pulley 21. A belt passes over the pulley 21 to a similar 15 pulley in the top of the car 14, to transmit rotation to the spindle of the aeroplane propeller 23.

24 is the operator's seat; and a shifter bar 25 extends to within reach of the operator, 20 so that the belt 22 can be shifted from the working pulley 21 to the idle pulley 20, whenever the aero-motor boat is moved over the water, and the propeller 23 is not required to be in use. The operator's seat 24 25 is arranged at the rear of the car 14, and any number of levers 24' may be arranged beside it to control the rudders at the rear of the car, or the slides 5, as may be necessary. At the rear thereof, just above the 30 propeller 19 is a funnel 27. Just above the seat 24 is an opening 29, to allow the operator to raise his head above the roof of the car and obtain a view of the surroundings, whenever he so desires.

35 On the front of the car is a pair of inclined supports 30, fastened together at the top adjacent the shaft of the propeller 23, and connected at their lower ends to a pair of outwardly-extending arms 31. These 40 arms or braces 31 carry in their outer ends, adjacent their point of connection with the diagonal members 30, a pair of downturned yokes 32, these yokes serving as supports for a pair of wheels 33, which support the 45 machine when it rests upon the ground. A similar wheel 33' is arranged under the rear part of the main frame 1. The shanks of the yokes slide through openings in the adjacent ends of the parts 30 and 31, being 50 held in place in any suitable way; and springs 31' are placed between the yokes 32 and the arms 30 to cushion the wheels 33. Similar cushioning means are employed in connection with the wheel 33'.

55 Supported between the wheels 33 and adjacent the bottom of the boat-shaped car are air tanks 34, one on each side of the center of the car 14; and a pair of air tanks 35 is supported by the wing frames 2, beneath the 60 openings 4. These air tanks 35 depend from vertical rods 36, connected to the lower side of the wing frames 2, and suitable stay rods 37, joined to the bottom of the wing frames 2 and the lower end of the rods 36, 65 hold the tanks 35 in proper relation to the

wing frames 3, and prevent them from swinging when the aeroplane is in flight. A similar air tank 35 is carried by the rear end or tail portion of the main frame 1, to buoy up the tail of the aero-motor boat 70 when the latter is traveling on the water. The tanks 34 are supported by vertical members 34', slidably secured to the arms 31. Cushion springs are coiled around the members 34' between the arms 31 and the 75 tanks 34. Rods 36 are slidably secured in bearing blocks supported by the stay rods 37, and springs 36' are placed on the rods 36 to cushion the three tanks 35. Such bearing blocks are fully shown at 35', at the 80 right on Fig. 3. The rods 36 are so connected to the springs 36' that the latter are compressed upward when the tanks are forced upward, and it will be seen that the springs for the tanks 34 and 35, and the 85 wheels 33 and 33', will minimize the liability of damage due to shocks when the aero-motor boat is traveling on land or over the surface of the water.

It will be understood that the tanks 35 90 are rigidly secured to the rods 36. The tanks 35 may be prevented from swinging around the rods in the bearings 35' either by means of a key and groove or by anchoring the ends of the tanks 35 with stay rods to 95 the wing and tail frames. Likewise, the rods 36 beneath the wing frames do not have to be arranged directly below the openings 4, but may be placed on either side thereof if desired.

The car 14 is held rigid with respect to the wing frames 2, and prevented from swinging beneath the same by means of stays 30', these stays being joined to the outer ends of the arms 31 and diagonal supports 30 at their lower ends, and to the lower side of the wing frames 2 at their upper ends.

A gasoline tank 41, which supplies fuel for the motor 17, is suspended beneath the 110 roof of the boat-shaped car, as shown on Fig. 4, and the exhaust pipe 42 of the engine passes out through the bottom of the car.

Fig. 5 shows a modification of motor boat 115 attachment for our aeroplane, consisting of an ordinary motor boat having a hull 14' of light but strong construction. The bow of this boat is covered over as shown at 38, and for this purpose a spray hood made of 120 canvas, similar to hoods commonly used for such purposes on motor boats, may be employed. The hull of the boat 14' is supported by means of hangers 40, connected to the sides of the frame 1 at their upper ends and 125 to the bow and stern of the boat at their lower ends. The engine, shown at 17 on Fig. 4, will be arranged beneath the hood, and this engine will rotate the propeller 19 when the boat rests upon the water and can 130

also be thrown in to transmit power to the propeller 23 when the machine is flying. In other words, the same power apparatus with all the appliances forming a part 5 thereof, as shown on Fig. 4, will be used in connection with the motor boat attachment 14', the power plant being located beneath the hood 38. There will be wheels 33 and air tanks 34 flanking the boat 14', but the 10 air chamber 16 beneath the bottom or floor of the boat, as shown on Fig. 4, will be dispensed with. The members 30 and 31 are employed in connection with the boat 14', the members 31 extending outward from the 15 side thereof and being connected at their outer ends to the members 30, which are fixed to the bow of the boat 14'. Braces 42' are joined to the outer ends of the members 30 and 31, and at their upper ends to the 20 framework of the hood 38.

When the aero-motor boat is flying, the propeller 19 of course will be uncoupled and the driving power will be supplied through the propeller 23. When it is desired to 25 alight on the surface of a body of water, the machine glides down until it reaches the water, and is caused to float upon the surface thereof by means of the air tanks 34 and 35, and the air chambers 16 in the bottom of the boat-shaped car 14. The air tanks 35 carried by the wing frames 2 and the tail frame will buoy up the main frame of the aeroplane and cause it to rest at all 30 times upon even keel. In other words, on account of the air tanks 35, the structure 35 will never rock about its longitudinal axis to such an extent as to submerge the tips of the wings 3, or about a transverse axis to such an extent as to cause the tail 1 to dip 40 into the water, while the air tanks 34 and the air chamber 16 in the bottom of the boat will support the car 14 high enough out of the water to give the operator ample chance to see where he is going, through the 45 openings 15 in the front of the boat. The propeller 19 in this case can be used to propel the machine, but, if desired, the propeller 23 may be thrown into operation also. To rise from the surface of the water, the 50 operator merely adjusts the angles of the main planes 3 to the required extent, and increases the power of the engine until the driving effort becomes great enough to lift the aeroplane and cause it to resume its 55 flight. Our improved aero-motor boat can be thus made to rise into the air from either the land or water, the wheels 33 and 33' serving in the former case, and the air tanks 34 and 35 in the latter.

60 When the machine is flying, the windows 15 in the front and the openings 27 in the back will allow the air to flow freely through the interior of the car 14 and reduce the resistance due to the air pressure, 65 as the machine moves forward.

We have shown and described our invention as comprising a motor boat attachment for a monoplane, but it is obvious that we may construct the same in the form of a biplane motor boat if desired.

We wish to reserve to ourselves the right to make certain small changes in the size, shape and arrangement of the parts, as fairly fall within the scope and nature of our invention. For example, in Fig. 5 we omit the air chamber shown at 16 on Fig. 4. Under certain conditions we might also omit the air tanks 34, using simply the air tanks 35 beneath the wings and the tail, to float the aeroplane when it rests upon the surface of 70 the water. The marine propeller 19 could be dispensed with, and the car 14 so formed that it would be suspended above the water. In this case the air propeller 23 would do 75 all the work and cause the machine to glide 80 along the water on the tanks 35.

Having thus described our invention, we claim as new and desire to secure by Letters Patent:

1. The combination of an aeroplane having wing frames and a tail frame, and means supported by said wing frames and the tail frame to float upon the surface of 90 a body of water and buoy up the aeroplane.

2. The combination of an aeroplane having wing frames and a tail frame, a boat-shaped car suspended beneath the aeroplane between the wings and adjacent the front end of the aeroplane, said boat-shaped car being adapted to rest upon the surface of 95 100 the water, and means carried by the wing frames and the tail frame of the aeroplane to rest upon the surface of the water in conjunction with the boat-shaped car, to prevent the wing frames or the tail frame from 105 being dipped into the water when the car is moved over the surface thereof.

3. The combination of an aeroplane having a boat-shaped car supported centrally of the wings and beneath the same, an aero-propeller mounted on the front of said car near the top thereof, a marine propeller mounted on the rear of the car near the bottom thereof, a motor carried by said car, a clutch for connecting and disconnecting the 110 power shaft of the motor to the marine propeller, fixed and idle pulleys upon the crank shaft of said motor, a belt connecting said motor to the shaft of the aero-propeller, and means for shifting said belt upon the fixed 115 120 or the idle pulley, as desired.

4. The combination of an aeroplane having a boat-shaped car supported beneath the framework thereof, an air chamber in the bottom of said car, means for increasing the 125 buoyancy of the said chamber, arranged beneath the car and on each side of the same, and means carried by the wings and tail of said aeroplane to rest upon the surface of a body of water, and buoy up the framework 130

thereof, whereby the wing frames and the tail frame will be prevented from dipping into the water.

5. The combination of an aeroplane and a boat-shaped car supported beneath the framework thereof, said car having an air chamber in the bottom thereof, a pair of air tanks connected to the said car beneath the bottom thereof, on either side of the same, and air tanks supported beneath the wing frames and the tail frame to rest upon the surface of a body of water and prevent the wing frames and the tail frame from dipping into the water.
10. 6. The combination of an aeroplane having wing frames and a tail frame, means suspended beneath the wing frames and the tail frame, adapted to rest upon the surface of a body of water to buoy up said wing frames and tail frame, and means comprising stay wires connected at one end to the said first-named means and to the wing frames and the tail frame at their other ends, to maintain said first-named means in proper relation to said wing frames and tail frame.
15. 7. The combination of an aeroplane having wing frames and a tail frame, and means supported yieldably by said wing frames and the tail frame to float upon the surface of a body of water and buoy up the aeroplane.
20. 8. The combination of an aeroplane and a boat-shaped car supported beneath the framework thereof, said car having an air chamber in the bottom thereof, a pair of air tanks yieldably connected to the said car beneath the bottom thereof, on either side of the same, and air tanks yieldably supported beneath the wing frames and the tail frame to rest upon the surface of a body of water and prevent the wing frames and the tail frame from dipping into the water.
25. 9. The combination of an aeroplane having wing frames and a tail frame, buoyant tanks supported beneath the wing frames and the tail frame to float upon the surface of a body of water and buoy up the aeroplane, rods secured to said tanks, bearings through which said rods pass, said bearings being rigidly supported below the lower

surface of the frames, and springs on said rods between the tanks and the lower surface of the frames, said springs being adapted to be compressed when the tanks are moved upward.

10. The combination of an aeroplane having wing frames and a tail frame, and air tanks resiliently connected to the opposite ends of said wing frames and the rear end of the tail frame to enable the aeroplane to float upon the surface of a body of water.

11. The combination of an aeroplane having wing frames and a tail frame, air tanks resiliently connected to the opposite ends of said wing frames and the rear end of the tail frame to enable the aeroplane to float upon the surface of a body of water, and means for holding said air tanks against rotation with respect to the aeroplane.

12. In an aeroplane, a boat-shaped car, a pair of tanks located adjacent the bottom of said boat-shaped car on both sides of the center, a pair of arms projecting laterally from the outer front face of said car, a pair of yokes mounted in said arms and resiliently connected thereto, wheels carried by said yokes, vertical members connecting said tanks to the car, and springs coiled around said vertical members to cushion said tanks.

13. In an aeroplane, a boat-shaped car having an air chamber in its bottom, a pair of tanks located adjacent the bottom of said boat-shaped car on both sides of the center, a pair of arms projecting laterally from the outer front face of said car, a pair of yokes mounted in the said arms and resiliently connected thereto, wheels carried by said yokes, vertical members connecting said tanks to the car, and springs coiled around said vertical members to cushion said tanks.

In testimony whereof we have signed our names to this specification in the presence of two subscribing witnesses.
